UNITED STATES PATENT OFFICE

ERNST BLOMQUIST, OF LOMBARD, ILLINOIS

SWITCH

Original application filed March 25, 1929, Serial No. 349,877. Divided and this application filed November 8, 1930. Serial No. 494,235.

The present invention relates to electric switches for opening and closing an electric circuit, and relates more particularly to disconnect switches arranged for gang operation whereby they are adapted to be simultaneously operated for cutting in and cutting out various electrical devices.

As is well recognized in the art when workmen are working around electrical devices it is particularly desirable, if possible, to have these devices entirely cut out of the associated electric circuits and preferably grounded where feasible. It is for such purpose that disconnect switches are interposed in the electric circuits including such devices. Where disconnect switches are arranged for gang operation, each gang including two, three, or more individual switches, it sometimes occurs that the operating means for simultaneously throwing all of the switches becomes disabled in such a manner that one or more of the individual switches are not thrown to their proper position with the remaining switches. It is old in the prior art to associate indicating mechanism with the gang operating means for indicating to workmen whether or not the gang or gangs of switches are in the proper position to allow them to work in and around the associated apparatus. Under the conditions just mentioned where one or more of the switches have not been moved to their proper position with the others, a condition exists wherein a part of the associated apparatus or devices is alive and a condition is thereby created making it dangerous for workmen to repair or replace, or otherwise work upon, said apparatus or devices.

Where the indicating device for the switches is associated with the gang operating mechanism it will be seen that there will be no indication whatsoever that one or more of the switches have been left unmoved, and the workmen will therefore have no indication that a dangerous condition exists.

The principal object of my invention is to remedy the defects and disadvantages of the prior art apparatus in the respects indicated above and, more particularly, to provide an improved means for indicating whether or not every blade of a gang switch has been moved to its proper position.

Another object of the present invention is to so arrange the indicating or signalling means in such a manner that the position of the switches corresponds to a dangerous condition will always be indicated unless each and every one of the blades is positively moved to its other position.

Other objects and advantages of my invention will be apparent to those skilled in the art after a consideration of the following detailed description of the preferred embodiment which is illustrated in the accompanying drawings, in which:

Figure 1 is a vertical elevation of a switch house and bus connecting cabinet, a portion of the front wall of the same being broken away to better show the switches and associated mechanism;

Figure 2 is a horizontal cross-section taken substantially along the line 2—2 of Figure 1; and

Figure 3 is an enlarged side view showing the arrangement of the operating means and the indicating means associated with each of the electric switches.

This case is a divisional application of my copending application, Serial No. 349,877, filed March 25, 1929, for a new and useful improvement in substations.

Referring now to the drawings, it will be observed that I provide a housing 1 which may be in the form of an enclosing switch house for enclosing and protecting the various switches and the other electrical devices operatively associated therewith and arranged to be conveniently accessible for purposes of inspection, repair or the like, as more clearly disclosed in the above entitled

copending application to which reference may be had for other details not forming a part of this invention. While in this case I have illustrated a switch house of the type 5 shown in my copending application of which this case is a division, it is to be understood that, for the purposes of the present invention, the switch house is utilized only for purposes of illustration and only to illustrate 10 one convenient form of housing for a gang or gangs of disconnect switches with which the present invention is more intimately connected.

Disconnect switches of various types are 15 adapted to be mounted on the interior of the housing 1, which switches may be arranged in various manners in different circuits as the occasion may demand. For purposes of illustrating the present invention I have 20 shown the housing 1 as provided with an upper separating wall or partition, preferably flame proof, designated by the reference numeral 2. Below the partition 2 may be mounted or installed the various electrical 25 devices referred to above, while above the partition I mount a pair of panels 5 and 6 formed of suitable material and serving as vertical walls of the housing structure for the purpose of supporting the various 30 switches.

The disconnect switches are all mounted in the section of the housing 1 above the partitioning horizontal separating wall 2. As shown in Figure 1, main bus disconnect 35 switch blades 8 and transfer bus disconnect switch blades 9 of the respective phases of the associated electric circuits are mounted one above the other by any suitable means 10, 11 and 12 on the panel 5. The switches 40 of the respective phases are separated from one another by suitable insulating transit barriers 15 of asbestos or the like, so that an arc at the disconnect switches of any one phase cannot be communicated to the other phases. Similar transit barriers at the top of 45 the switches 8 and 9, as indicated at 16, prevent an arc which may be generated at one of the disconnect switches from extending to the top of the switch housing.

50 Mounted on the other panel 6 are the switch blades 18 and 19 of the respective phases, as by suitable means 20, 21 and 22, and these switches are likewise separated by suitable transit barriers 25 and a similar barrier 26 55 is placed above the switches to prevent an arc from being extended upward to the top of the housing.

Any suitable means may be provided for 60 operating the disconnect switches 8, 9, 18 and 19. As best shown in Figure 2, the disconnect switches 8, 9, 18 and 19 are arranged in gangs including the individual switches for each gang. Each gang is adapted to be separately operable by any suitable means, as 65 just stated, and by way of example I show

an operating mechanism associated with switches 8 and 18 in Figure 2. This operating mechanism may take the form of a journal shaft 30 carried by brackets 31 mounted on the panels 5 and 6, there being a number of these brackets for adequately supporting the journal shafts. In Figure 2, I have shown a journal shaft associated with each of these gangs 8 and 18, but it is to be understood that gangs 9 and 19 also are operated 75 by the same means in substantially the same manner.

As best shown in Figure 3, each of the shafts 30 is provided with a plurality of arms 33, one for each of the individual 80 switches comprising the disconnect switch gang. The arms 33 are secured in any desired manner to the shaft 30 associated therewith, and an insulating link 34 is pivotally mounted on the outer end of each of the arms 85 33 and is projected or extended through an opening in the supporting panel or end wall of the housing. The inner end of each of the links 34 is connected to the switch blade 35 of the switch proper. The latter cooperates in the usual manner with the switch contact 36.

An operating arm 38 is secured to the shaft 30, preferably at one end thereof as indicated in Figure 2, and extending downwardly from the outer end of the operating arm 38 is a switch operating rod 40. The rod 40 is adapted to be actuated in any desired manner, either manually or by motor, to rock the shaft 30 and swing the arms 33 to move the blades 35 of the disconnect switches associated with that particular shaft. In this way the blades of the switches are all simultaneously moved into and out of circuit closing position.

Figure 3 illustrates in detail the above described mechanism for moving the switch blades of each of the switches into and out of circuit position, and it is to be understood that the switch blades of each of the gangs 8, 9, 18, and 19 are operated by the same or similar structure. For purposes of clarity, however, the operating means for the different gangs has been omitted from Figure 1, it being deemed necessary only to show the situation of the switch operating means to one 105 set or gang of disconnect switches only.

Where, as in this case, each switch gang comprises three individual switches, it becomes desirable to know whether or not all of the switches have been properly moved 110 when the switch operating rod 40 for each of the gangs has been actuated. As a rule, the various switches are enclosed as illustrated and a direct observation of whether or not all of the switches have been actually operated when the lever 40 was moved is not possible. Referring more particularly to Figure 2, it will be understood that in the event that one of the shafts 30 breaks or ruptures between the individual switches certain of the 115 120 125 130

switches will then be shifted when the rod 40 is actuated but others will not. Hence, if an operator after operating the rod 40 in the usual manner attempts to make the usual 5 repairs or adjustments he will be confronted with the dangerous condition of working on live connections and through which considerable current may be flowing. This same dangerous condition will prevail should one of 10 the links 34 break or become disconnected or should one of the cranks 33 become loose on the shaft 30 and fail to be rotated thereby.

In order to clearly indicate at a point capable of direct observation whether or not 15 all of the individual switches have been moved to the proper position when the operating rod 40 of that particular gang has been shifted, I provide an individual indicator for each of these switches making up the different 20 gangs. Referring more particularly to Figure 3, an insulating rod 45 is pivoted to each of the switch blades 35 and is extended inwardly and downwardly toward the horizontal wall or partition 2. Mounted centrally 25 on the partition 2 and inside the housing enclosing the various disconnect switches is a shaft 47, preferably carried by brackets 48 secured in any desired manner to the partition 2. The shaft 47 carries a number of signal 30 flags or indicators 50 which are freely rotatable on the shaft 47 and each of which is provided with an upwardly extending arm 51, as best shown in Figures 1 and 3. These arms 51 are operatively connected with the 35 inner ends of the insulating rods or links 45.

Suitably associated with each of the signals or indicators 50 are the indicator flags 53 proper which are formed to extend downwardly through suitable openings in the horizontal wall 2 so that their position may be 40 visible to the operator or repair man. The flags proper 53 may be suitably colored if desired.

It is to be noted that the signals or indicators just described are those which are associated with the individual switches making up the gang switch 19. Referring now more particularly to Figure 3, when the shaft 30 is rocked to open all of the switch blades 35 the 45 arm 51 will be rocked in a clockwise direction and will withdraw through the horizontal partition and into the housing 1 the visible portion 53 of the indicator signal. By the disappearance of all three signals associated 50 with the three switches making up the switch gang 19 the operator will know that all of the three phases are open and that as far as this circuit is concerned it is safe to remove or replace fuses, or perform any other duties 55 required.

From Figure 1 it will be observed that the indicators associated with the disconnect switch gang are of somewhat different formation than the corresponding indicators 50 associated with gang 19. The switch blade

60 of each of the switches making up the gang 9 has a slotted connection with an insulating rod 61 corresponding to the insulating rod 45 and which, at its lower end, is pivoted directly to the indicator or signal 62 in such a 70 manner that when the switch blade 60 is closed the indicator 62 is withdrawn into the housing to the horizontal partition 2. On the other hand, when the blade 35 of each of the switches making up the gang 19 is closed, the 75 signal or indicator is in position to project the visible portion 53 thereof downwardly to the horizontal partition 2 so as to display the signal or indicator to view. This particular arrangement is only one of many arrangements it is possible to effect according to my present invention. As pointed out above the gang switch 9 is a grounding switch whereas the gang switch 19 is a bus disconnect switch. In this particular arrangement, 80 therefore, where some particular piece of apparatus is to be isolated it is necessary to disconnect the same from the line and, if possible, to ground the apparatus. As shown in Figure 1, therefore, the signals associated 85 with the individual grounding switches are only projected into view when one or more of the individual switches is not closed and is not, therefore, completely grounding the apparatus. On the other hand, the signals associated 90 with the bus disconnect switch gang 19 are only projected when the individual switches are closed.

Under the conditions just stated, that is, 95 when some particular piece of apparatus is to be isolated and grounded, it is essential to know that all of the bus switches are opened and that all of the ground switches are closed. When this is the case, according to the present invention, all of the visible portions of the signals 50 and 62 are withdrawn 100 into the housing above the partition 2 and hence practically out of view of the operator. Should, however, some of the connections between the individual switches and the operating mechanism fail for one reason or another, 105 the signal for that particular switch will remain projected through the partition 2 and will therefore serve to attract the attention of the operator and indicates that the apparatus 110 is unsafe to work upon or around.

One important feature of the present invention relates to the fact that the signals 50 and 62 are so arranged that they tend to move by gravity to a position corresponding to a 115 dangerous condition. This construction is such that unless the bus switches are positively moved to their open position, or unless the grounding switches are positively moved to their closed position, the signals will be 120 visible to apprise the operator that it is unsafe to work on or around the apparatus. Thus, if any of the connections between the 125 switch blades of the various switches and the corresponding indicators become disabled or 130

broken, whereby the indicators are no longer responsive to the position of the switch blades, the signals immediately fall by gravity into a position indicating the unsafe condition of the apparatus. In this way there is extremely little likelihood of the signals or indicators failing in their purpose to indicate when the apparatus is unsafe to work upon or around.

10. While I have shown and described the preferred embodiment of the present invention, it is to be understood that my invention is not to be limited to the specific means shown and described, but that, in fact, widely different 15 means may be employed in the practice of the broader aspects of my invention.

What I claim, therefore, and desire to secure by Letters Patent is:

1. A switch comprising a switch blade and 20 a switch contact, means for moving the blade into and out of engagement with the contact, an insulated rod operated by the blade, and means controlled by the rod for indicating the open or closed position of the switch 25 blade.
2. In combination, a plurality of switches, common operating means for simultaneously opening and closing the switches, and individual signalling means associated with each 30 switch for indicating the open or closed position of the switch.
3. In combination, a panel, a plurality of switches mounted on one side of the panel and each including a switch contact and a 35 switch blade, means including an operating member on the other side of said panel for controlling the switches, and additional means associated with each of said switches for indicating the open or closed position of 40 said switches.

4. In combination, a plurality of switches, each including a switch contact and a switch blade, a housing enclosing said switches, means for moving the switch blades into and 45 out of closed circuit position, said means comprising a shaft, arms fixed to said shafts, link means connecting each arm to one of the switch blades, means for rocking said shaft for simultaneously opening and closing all 50 of said switch blades, and indicating means associated with each switch for showing the position of each switch, and including a signal flag for each switch blade and projecting through one wall of the housing.
5. In combination, a plurality of switches, each including a switch contact and a switch blade, a housing enclosing said switches, means for moving the switch blades into and 55 out of closed circuit position, said means comprising a shaft, arms fixed to said shaft, link means connecting each arm to one of the switch blades, means for rocking said shaft for simultaneously opening and closing all 60 of said switch blades, and indicating means associated with each switch for showing the

position of each switch, said indicating means including a journal shaft mounted inside the housing adjacent one wall thereof, signal flags journaled on said shaft and including an indicator portion extending 70 through said wall of the housing, and means connecting each of said flags to one of the switch blades.

6. In combination, a plurality of switches, each including a switch blade movable to 75 open and closed circuit position, a housing for said switches, one set of said switches being mounted on one vertical wall of the housing and another set being mounted on another vertical wall of the housing, operating means for controlling all of said switch blades, and indicating means associated with each switch for showing the position of each switch, said indicating means including a shaft mounted inside the housing and adjacent the horizontal bottom wall thereof, signal flags journaled on said shaft and including indicator portions extending through 80 said bottom wall of the housing, and means connecting each of said flags to different ones 85 of the switch blades.

7. A switch comprising a switch blade and a switch contact, means for moving the blade into and out of engagement with the contact, and means associated with the blade for indicating the open or closed position thereof, and including an indicator adapted to be moved by gravity to one of its indicating 95 positions.

8. A switch comprising a switch blade and 100 a switch contact, means for moving the blade into and out of engagement with the contact, and means associated with the blade for indicating the open or closed position thereof and including an indicator adapted to be 105 moved by gravity to the indicating position which corresponds to a dangerous condition of the switch.

9. A switch comprising a switch blade and a switch contact, means for moving the 110 blade into and out of engagement with the contact, a rod operated by the blade, and means controlled by the rod for indicating the open or closed position of the switch blade and including an indicator adapted to 115 be moved by gravity to one of its indicating positions in case of failure of said rod.

10. In combination, a plurality of switches, common operating means for simultaneously opening and closing the switches, certain of 120 said switches establishing a dangerous condition when open and other of said switches establishing a dangerous condition when closed, and signalling means associated with each switch and operatively connected therewith to indicate when any of the switches are in a position to establish a dangerous condition.

11. In combination a plurality of switches, common operating means for simultaneously 125

opening and closing the switches, certain of
said switches establishing a dangerous condition
when open and other of said switches
establishing a dangerous condition when
closed, visible signal flags, one for each
switch, and connecting means placing each
flag in operative association with the corresponding
switch, said signal flags being
adapted singly or collectively to move by
10 gravity to a position indicating a dangerous
condition if said connecting means fails.

In witness whereof, I hereunto subscribe
my name this 6th day of November, A. D.
1930.
